MARK JAY SAMUELS, OF NEW YORK, N. Y., ASSIGNOR TO LYRAPHONE COMPANY OF AMERICA, OF WASHINGTON, DISTRICT OF COLUMBIA, A CORPORATION OF DELAWARE.

TALKING-MACHINE.

1,287,763.

Specification of Letters Patent. Patented Dec. 17, 1918.

Application filed November 23, 1915. Serial No. 62,979.

To all whom it may concern:

Be it known that I, MARK JAY SAMUELS, a citizen of the United States, and a resident of the borough of Manhattan, city, county, and State of New York, have invented certain new and useful Improvements in Talking-Machines, of which the following is a specification.

My invention relates to talking machines and particularly to the means for connecting the reproducer or sound box to the sound amplifier or horn.

Some of the objects of my invention are to eliminate the false and impure sounds sometimes experienced in phonographs of ordinary construction; to provide a simple means for attaching and detaching the tone arm from the amplifier, to permit easy motion thereof in all directions, and to effect a more perfect contact of the needle and record. Other objects of my invention will appear in the specification and will more particularly be referred to in the claims.

In talking machines of the ordinary construction, a metallic member known as a tone arm is used to connect the sound amplifier with the reproducer. The tone arm is generally so arranged that the reproducer is free to move about a vertical axis, so that the needle may follow the grooves in the record and is also free to move in a vertical direction to compensate for any warping of the record or other inequalities in its surface. Provision is usually made for these movements of the reproducer, either by utilizing a ball and socket joint between the end of the amplifier and the adjacent end of the tone arm, or by pivoting the entire tone arm to swing about a horizontal axis at its point of attachment to the amplifier and pivoting the end of the tone arm adjacent the reproducer to the remainder of the tone arm to permit of the vertical movement of the reproducer. In the first case, there is a ball and socket joint between two metallic members, which results in a considerable lost motion and therefore permits of the vibration of one member with respect to the other. In the second case, where the two simple pivoted joints are used, while there is not as much lost motion in either joint as in the ball and socket joint, the fact that there are two joints between metallic

members, instead of one, renders this construction as unsatisfactory as the ball and socket construction.

I have found that the ordinary metallic tone arm, which tapers throughout its length, constitutes, in itself, a tone amplifier. But its construction being necessarily inexact and its freedom of vibration being impeded, both by its conformation and material, and by the fact that it contacts with other portions of the apparatus, the amplification is not true and overtones are introduced. Also the vibration of the tone arm mechanically, such as results from the scratching of the needle, introduces into the tone, certain extraneous sounds, which are very disagreeable and objectionable. These sounds are particularly evident when the periodicity of the mechanical vibration of the tone arm approaches the natural periodicity of the arm itself. It is evident that the vibration of the tone arm from any cause whatever will, if there be any lost motion between it and any other parts of the device, cause a chattering between the relatively movable portions.

Another disadvantage of the present use of metallic tone arms, is the fact that the needle often jumps from contact with the record, due to some imperfection in the record or the collection of dust or dirt thereon. This jumping of the needle destroys the continuity of tone and also produces any chattering at the joints.

With a view to eliminating all the disadvantages above noted, I have constructed my tone arm of nonresonant material, preferably flexible or elastic. By making the tone arm non-resonant, I avoid any vibration therein and confine the amplification of the sound entirely to the amplifier proper. The shape of the tone arm therefore may be any convenient one, since it performs no other function with respect to the sound, than to transmit it in its unamplified condition from the reproducer to the amplifier. All that is required is a relatively unobstructed passage, in which the air can vibrate.

The tone arm being non-resonant, the matter of any lost motion connection at the joint between the tone arm and amplifier becomes unimportant, since no vibration is

produced by resonance, and moreover, the tone arm being preferably of a flexible material, vibration at the joint between the amplifier and tone arm, will have no bad effect.

If my improved tone arm is made from elastic material, such for instance, as a soft rubber, it forms a cushion for any possible vertical movement of the reproducer, thus tending to hold the needle to its work and to more accurately follow the wave conformations in the record, thus producing a purer tone with less wear upon the record. Such an elastic tone arm also furnishes convenient means for attaching and detaching the tone arm from the amplifier and from the reproducer, as will be hereinafter pointed out.

Referring to the drawing,

Figure 1 is a plan view of a talking machine, to which my improved tone arm is applied;

Fig. 2 is a side elevation, partly in section, of this talking machine; and

Fig. 3 is a fragmentary sectional view, showing the means for attaching the tone arm to the amplifier.

The phonograph may be of any desired type and may be provided with any suitable record supporting means, such, for example, as the disk 5. The amplifier, which, in the type of machine illustrated, is for the most part concealed, terminates in the rigid tubular member 6. The tone arm 7 serves to connect the reproducer 8 to the end 6 of the amplifier.

As herein shown, the tone arm comprises a tube of flexible non-resonant material, such, for example, as soft rubber. At one end the tone arm receives the extension 9 of the reproducer. If the tone arm is elastic, as is preferable, it is apparent that the reproducer will, in this way, be held in position in the end of the tone arm, without the necessity of any retaining means.

The other end of the tone arm is preferably provided with an elbow in order that it may be connected conveniently to the end 6 of the amplifier. As is shown in Figs. 2 and 3, the end 6 of the amplifier is provided with circumferentially extending slots 10, which are adapted to receive the pins 11 secured to the end of the tone arm. In order to attach the tone arm to the member 6, it is merely necessary to compress the tone arm, so that the pins 11 may be inserted in the slots 10 and then release the compression. The result is that the tone arm is firmly held within the member 6 by the pin and slot connection 10-11, but is permitted, by reason of the extent of the slots, to rotate sufficiently to permit the needle to move across a record when placed in position on the disk 5.

Because of the flexibility or elasticity of the tone arm 7, it is unnecessary to provide

any pivot to permit vertical movement of the reproducer 8.

When the talking machine is not in use, the reproducer is preferably elevated from the record supporting disk and in order to retain it in elevated position, I provide a suitable bracket or rest, as shown at 12 in the drawing.

The advantages of using a tone-arm of flexible, non-resonant material are that such an arm can be easily and cheaply manufactured, and renders the assembling and disassembling of the device ready and convenient. Furthermore, such a tone-arm will be durable, since it is pliable and will therefore not be so liable to crack when used. Furthermore the pliable, flexible nature of the tone-arm helps to deaden the undesirable noises coming from the operating parts of the talking machine, since the walls of the tone-arm are soft and yielding and will therefore act to efficiently deaden the sounds which it is not desired to be transmitted. These advantages of the use of a flexible, non-resonant tone-arm are not inconsistent with the mounting of such tone-arm in such a manner that the same will not be flexed or distorted during the operation of the machine. Flexure or distortion of the tone-arm during the operation of the machine are to be avoided since such action will affect the pitch of the tones transmitted and will also act to more quickly wear out the tone-arm and cause the same to crack when in use. I am thus enabled to combine the advantages specified in an economical and efficient manner which at the same time avoids disadvantages which might otherwise be considered to follow from the use of a tone-arm not having the properties already specified.

The method of using my invention should be apparent from the above, and need not be reviewed.

While I have described but a single embodiment of my invention, it is to be understood that I do not wish to limit myself to any particular embodiment, since obviously many changes may be made therein, without departing from the spirit of my invention.

What I claim is:

1. In a talking machine, a tone-arm for connecting the movable reproducer to the relatively stationary amplifier of a talking machine, said tone-arm comprising a tube of flexible non-resonant material, said tube being the sole means interposed between said reproducer and said amplifier and being adapted to move without substantial flexure with relation to the amplifier.

2. In a talking machine, a rigid amplifier, a movable reproducer, a non-resonant tone-arm of soft rubber constituting the sole means interposed between the amplifier and

reproducer, and means for permitting free movement of the tone-arm relative to the amplifier at the point of junction of the two without substantial flexure of said tone-arm.

5 3. In a talking machine, a metallic amplifier, a reproducer, a non-resonant soft rubber tone-arm connecting the reproducer and the amplifier and being the sole connecting means interposed between the two, and joining means at the junction of the amplifier and tone-arm permitting free movement of the tone-arm with respect to the amplifier without substantial flexure of said tone-arm.

10 4. In a talking machine, a stationary metallic amplifier, a reproducer, a non-resonant soft rubber tone-arm, said tone-arm comprising the sole connecting means between the reproducer and the amplifier, said tone-arm being connected to the amplifier so as

to permit free movement of the tone-arm 20 without substantial flexure of the same.

5. In a talking machine, a sound amplifier having a hollow cylindrical end provided with circumferentially extending slots, a reproducer, and means for connecting the reproducer to the end of the amplifier, said means comprising a tube of flexible material adapted to receive the reproducer in one end and provided at the other end with a plurality of stationary pins adapted to be 30 received within said slots.

In testimony whereof I have signed this specification in the presence of two subscribing witnesses.

MARK JAY SAMUELS.
